US00D834186S

(12) **United States Design Patent** (10) Patent No.: **US D834,186 S**
(45) Date of Patent: ** Nov. 20, 2018

(54) **FLUID CONNECTOR COMPONENT**

(71) Applicant: **NORDSON CORPORATION**,
Westlake, OH (US)

(72) Inventors: **Francis J. Lombardi, III**, Erie, CO
(US); **Derrick S. Sjodin**, Bloomfield,
CO (US)

(73) Assignee: **Nordson Corporation**, Westlake, OH
(US)

(**) Term: **15 Years**

(21) Appl. No.: **29/561,327**

(22) Filed: **Apr. 15, 2016**

Related U.S. Application Data

(62) Division of application No. 29/523,796, filed on Apr.
14, 2015, now Pat. No. Des. 757,260, which is a
division of application No. 29/466,839, filed on Sep.
12, 2013, now Pat. No. Des. 730,518.

(57) **CLAIM**

The ornamental design for a fluid connector component,
therefor as shown and described.

DESCRIPTION

FIG. 1 is a rear isometric view of a fluid connector component showing our new design;

FIG. 2 is a front isometric view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The broken lines in the figures are shown for the purpose of
illustrating boundaries of the claimed design and the areas
inside the broken line boundaries form no part of the claimed
design.

1 Claim, 5 Drawing Sheets
